DESIGN FOR A CHAIR

James E. Bales, Aurora, Ill., assignor to Lyon Metal Products, Incorporated, Aurora, Ill., a corporation of Illinois

Application June 21, 1939, Serial No. 85,607

Term of patent 14 years

To all whom it may concern:

Be it known that I, James E. Bales, a citizen of the United States, residing at Aurora, in the county of Kane and State of Illinois, have invented a new, original, and ornamental Design for a Chair, of which the following is a specification, reference being had to the accompanying drawing, forming a part thereof.

The figure is a perspective view of a chair,
embodying my new design.

The dominant feature of the design resides in the chain back portion in association with the frame portion of the chair as shown.

I claim:

The ornamental design for a chair, substantially as shown and described.

JAMES E. BALES.
